RADIOGRAPHIC INSPECTION METHOD

Russell G. Rhoades, San Francisco, Calif., assignor to Bechtel Brothers McCone Company, a corporation of Delaware

Application June 24, 1946, Serial No. 678,783

2 Claims. (Cl. 250—65)

1

The present invention relates to the radiographic examination of welds and more particularly to an improved method and apparatus for radiographing circumferential welds in pipe lines and the like.

The radiographic examination of welds in pipe lines presents problems not encountered in the radiographing of welds in pressure vessels such as boilers which are provided with openings through which either a radiation emanating means or a film carrier may be introduced into the interior of the vessel. Pipe lines are laid in lengths of many miles and are devoid of any such openings, and this has made it necessary to take advantage of the open end in order to obtain the necessary access to the interior thereof for radiographic weld inspection.

Where radiographic inspection of pipe line welds is effected by introducing through an open end of the line either a film carrier or a radiation emanating means in the form of X-ray apparatus or a capsule of radioactive material, an interruption of construction work on the pipe line is necessary for each inspection. If, on the other hand, both the source of radiation and the film are disposed exteriorly of the pipe line, at least two separate exposures are necessary to inspect welds even where the pipe is of small diameter, and methods in which both the film and source of radiation are outside the pipe line are impracticable for other reasons when the pipe is of large diameter.

The principal object of my invention is to make possible the radiographic examination of pipe line welds by a single exposure without requiring access to an open end of the line.

A further and more specific object of my invention is to provide apparatus facilitating the carrying out of the radiographing method of my invention.

The foregoing principal object, together with other objects and advantages which will appear hereinafter, is accomplished, in general, by making a relatively small temporary opening in the wall of a pipe line adjacent but spaced from a circumferential weld therein, and utilizing said opening to introduce into the interior of the pipe line a source of radiation; so positioning the latter as to insure a clear path for radiation therefrom to the circumferential weld to be radiographed and through said weld to a film held on the exterior of the pipe over the weld. After the necessary exposure time has elapsed, the radiation source is withdrawn and the temporary opening, which is of only sufficient size

to freely admit a holder for the radiation source, is permanently sealed.

The method and apparatus by which the foregoing objects are attained will be best understood from the following description of preferred procedure and apparatus, reference being had to the accompanying drawing, forming a part of this specification, in which:

Figure 1 is a perspective view of a preferred form of apparatus embodying the present invention; the same being illustrated in place on a pipeline;

Figure 2 is a detail view of a portion of the apparatus illustrated in Figure 1; and

Figure 3 is a detail view illustrating a preferred way of sealing the temporary opening referred to herein.

In Figure 1 of the accompanying drawing there is illustrated a portion of a conventional pipe line 10 provided with the usual covering 11 and constructed in sections joined together by circumferential welds such as that illustrated at 12.

According to the present invention, a radiograph of any circumferential weld 12 in a pipe line 10, which may extend for many miles, can be made without access to an open end of the pipe line. To facilitate the carrying out of the radiographing method of the present invention, there is preferably provided apparatus of the character illustrated in Figures 1 and 2 which comprises an orienting device 15 adapted to rest in stable equilibrium on the curved upper surface of a cylindrical object such as a pipe line 10. For this purpose the device 15 is preferably made in the form of a plate having four legs 16 by means of which the device may be firmly and stably supported on the curved surface of a pipe during any period required for a complete radiograph exposure.

Secured to the orienting device 15 is a carrier 18 preferably in the form of a tube secured to the orienting device 15 by welding as indicated at 19. The tube 18 is curved as indicated in Figures 1 and 2 and proportioned so that its lower end lies outside of the area which the orienting device 15 overlies when it is disposed in the operating position in which it is shown in Figure 1.

When the apparatus is to be used, there is extended through the tube 18 an assembly consisting of a flexible wire 21 the upper end of which is secured to a handle 22 provided with a hooked portion 23 adapted to engage over the upper end of the tube 18. Attached to the lower end of the flexible wire 21 is a spring 24 the lower end of which is in turn connected to a second flexible

wire 25 provided with a hook 26 at its lower end. Removably secured to the lower end of the wire 25 by the hook 26 is a conventional radium capsule 27 which is preferably employed as the radiation emanating means in the practice of the present invention, although equivalent devices such as X-ray emanating means are, of course, well known in the art.

The length of the wire and spring assembly 21, 24, 25 is so proportioned to the length of the tube 18 that when the radium pill 27 is engaged in the open lower end of the tube 18 as shown, substantial tension must be applied to the spring 24 in order to engage the hook 23 over the open upper end of the tube 18. This spring tension serves to maintain the radium capsule 27 in position at the lower open end of the tube 18.

In carrying out the method of the present invention utilizing the above described apparatus, which is known in the art as a "jig," a temporary opening such as that illustrated at 30 in Figure 1 of the accompanying drawing is made in the wall of the pipe line at such a distance from the plane of the weld 12 as will bring the radium capsule 27 into the general plane of the weld 12 when the jig is positioned as illustrated in Figure 1 with the tube 18 extending through the temporary opening 30. It is also to be noted that the tube 18 is so positioned with respect to the orienting device 15 that, when the latter is in the stable position illustrated, the radium capsule 27 is substantially on the longitudinal axis of the pipe line. With the device thus positioned, a film 32, which is preferably placed in position before the tube 18 is inserted through the hole 30 and which overlies all of the weld 12 exteriorly of the pipe line 10, will be uniformly exposed and will provide a radiograph of uniform density showing all portions of the weld 12.

After the necessary exposure time, determined in a manner well known in the art, has elapsed, the tube 18 is withdrawn from the temporary opening 30 by lifting the orienting device 15 pref-

erably by such means as the hooked handle 33 illustrated in Figure 1, and the temporary opening is permanently sealed by means such as a screw plug 44 (Figure 3) inserted in the opening 30 and welded in place as illustrated at 45.

What is claimed is:

1. A method of radiographing a circumferential weld in a pipe line access to which from an open end is impracticable, comprising the steps of making a temporary opening in the wall of said pipe line at a point adjacent said weld, introducing radioactive material through said temporary opening, positioning said radioactive material in the general plane of said weld and substantially on the axis of said pipe line, exposing to the emanation of said radioactive material film wrapped around said pipe line exteriorly thereof at said weld, withdrawing said radioactive material through said temporary opening, and sealing said temporary opening.
2. A method of radiographing a circumferential weld in a pipe line access to which from an open end is impracticable, comprising the steps of making a temporary opening in the wall of said pipe line at a point spaced a predetermined distance from said weld, utilizing a jig having orienting means engageable with the exterior wall of said pipe line adjacent said temporary opening and radioactive material positioning means offset with respect to said orienting means by the aforesaid predetermined distance and extendible through said opening to introduce radioactive material through said temporary opening and position said material in the general plane of said weld and substantially on the axis of said pipe line, exposing to the emanation of said radioactive material film wrapped around said pipe line exteriorly thereof at said weld, withdrawing said radioactive material through said temporary opening, and sealing said temporary opening.

RUSSELL G. RHOADES.
